Inventor
Warner Palmer,

By *Clarence A. O'Brien*

Attorney

UNITED STATES PATENT OFFICE.

WARNER PALMER, OF MEADOWLANDS, MINNESOTA.

THAWING DEVICE.

Application filed April 3, 1926. Serial No. 99,540.

This invention relates to a thawing device for motor vehicle engine radiators and has for an object to provide a thawing attachment for automobiles employing water cooling systems for the motors thereof whereby such steam as may be generated in the cooling system of the automobile may be used for thawing the same when frozen, thus dispensing with the heretofore practiced method of thawing the systems as by pouring hot water into the radiator thereof or throwing hot water over those parts believed to be clogged by the frozen water.

An additional object is to provide a thawing means which can be readily applied to various makes of automobile radiators without undue alteration of the same or without effecting the operation of the engine, the device being also well adapted for ready attachment to the radiators at the time of manufacture or subsequent thereto.

Other objects will become apparent as the nature of the invention is better understood, the same comprising the novel form, combination and arrangement of parts herein-after more fully described, shown in the accompanying drawing and claimed.

In the drawing wherein like reference characters indicate corresponding parts throughout the several views:

Figure 1 is a front elevation of the conventional automobile engine radiator equipped with my novel thawing means.

Figure 2 is a fragmentary side elevation thereof, the thawing means being disclosed in transverse cross section, and

Figure 3 is a fragmentary top plan of the radiator that is equipped with the thawing means.

Now having particular reference to the drawing, 5 indicates generally a motor vehicle engine radiator that is provided at its top side with the usual filler neck 6 within which is arranged one end of an overflow pipe 7 that leads downwardly from the radiator and terminates at one side thereof slightly beneath the same.

My novel thawing means constitutes the provision of a sheet metal pan 8 that is open at its top side and that is so shaped as to receive within its open side the lower edge of the radiator as more clearly disclosed in Figure 2. The pan may be soldered, welded, or otherwise suitably secured in permanent association with the radiator and is of such construction as not to materially

detract from the appearance of the radiator. Formed integrally with the pan at the end thereof adjacent the discharge end of the overflow pipe 7 is a closed extension 9 in communication with the pan, the top wall of which is formed with an opening for receiving the discharge end of the overflow pipe in order that the steam from the radiator may be conveyed into said pan. 65

The front wall of the pan is formed throughout its length with escape openings 10 while formed at the front edge of the pan is an upwardly extending skirt 11 in spaced relation with the front of the radiator, the same terminating at its upper edge slightly above the lower portion of the radiator shell in order that the suction created by the cooling fan located directly rearwardly of the radiator (not shown) will draw the steam 70 through the bottom of the radiator, and over the water exit pipe 5' thereof for thawing out any frozen water in the radiator or the pipe wherein practically all the freezing occurs. It will be noted that the steam in 75 the pan comes into direct contact with the lower end of the radiator and therefore has a heating effect on said end which will be transmitted to the water therein and because of the circulation of the water, the temperature thereof will be raised. 80

It is to be further noted that the radiators usually freeze, when the automobile is in motion, at the bottom, and therefore this heating of the bottom end of the radiator is very beneficial 85 and tends to eliminate the tendency of the freezing of the water in the lower portion of the radiator.

For permitting the steam to escape without passing into the pan 8, the bottom wall 95 of the extension 9 is formed with a gate valve opening 12, Figure 2. It will thus be seen that I have provided a highly novel, simple and efficient thawing device for motor vehicle radiators that is well adapted for all the purposes heretofore designated, and even though I have herein shown and described the device as consisting of certain detail structural elements it is nevertheless 100 to be understood that minor changes may be made therein without effecting the spirit and scope of the appended claims.

Having thus described the invention, what I claim as new and desire to secure by Letters Patent is:—

1. In a thawing device for radiators provided with overflow pipes, a steam pan

adapted for arrangement upon the lower side of a radiator and for communication with the overflow pipe of the radiator, the front wall of the pan being provided with steam

5 discharge openings and means for directing the steam upwardly after passing through said openings so that the same may be drawn through the radiator by suction.

2. In a thawing device for radiators provided with overflow pipes, a steam pan 10 adapted for arrangement upon the lower side of a radiator and for communication with the overflow pipe of the radiator, the front wall of the pan being provided with steam 15 discharge openings and means for directing the steam upwardly after passing through said openings so that the same may be drawn through the radiator by suction, and means for permitting the steam to exhaust 20 from the pan at the rear thereof when the use of the steam from the overflow pipe is not desired.

3. In a thawing device for radiators provided with overflow pipes, a steam pan 25 adapted for arrangement upon the lower side of a vehicle radiator, a closed extension formed upon the rear side of the pan for communication with the overflow pipe of the radiator, the front wall of the pan being 30 provided with steam discharge openings, and

means at the front end of the pan for guiding the steam upwardly to the radiator in order that the same will pass therethrough by suction.

4. In a thawing device for radiators provided with overflow pipes, a steam pan 35 adapted for arrangement upon the under side of a radiator, and for communication with the overflow pipe of the radiator, the front wall of the pan being provided with steam 40 discharge openings, and a skirt attached to the front of the pan and disposed upwardly in spaced relation with the front of the radiator, the upper edge of said skirt being inclined inwardly towards the radiator. 45

5. In combination with a radiator including an overflow pipe, a pan attached to the under side of the radiator and extending throughout the length and breadth thereof 50 and connected with the overflow pipe, the front wall of the pan being provided with a plurality of discharge openings, and means for guiding the steam upwardly after the steam passes through said openings so that the same will be drawn through the radiator 55 by suction.

In testimony whereof I affix my signature.

WARNER PALMER.
